SEWING MACHINE

William A. Andres, Bridgeport, Conn., assignor
to The Singer Manufacturing Company, Elizabeth, N. J., a corporation of New Jersey

Application April 10, 1941, Serial No. 387,894

5 Claims. (Cl. 112—210)

This invention relates to sewing machines and has for its object to facilitate manipulation of an oil-tight device actuatable from the exterior of the sewing machine frame for controlling a member disposed within said frame.

More specifically, the invention has for its object to facilitate adjustment of an actuating eccentric, housed in an oil-tight sewing machine frame, by the provision of oil-tight means readily operable from the exterior of said frame for controlling an adjusting member disposed within the frame and associated with said eccentric.

With the above and other more specific objects in view, the invention consists in the adjusting-member controlling device for an actuating eccentric, as hereinafter described in connection with the accompanying drawing which illustrates a preferred embodiment of the invention and in which:

Fig. 1 represents a longitudinal section of the work-arm of a feed-off-arm sewing machine containing the present improvement. Fig. 2 represents a transverse section of the work-arm of the machine in a vertical plane containing the axis of rotation of the feed-actuating shaft. Fig. 3 is a detail view of the feed-eccentric adjusting member from the recessed side face thereof. Fig. 4 represents a vertical section taken transversely of the work-arm and on substantially the axis of rotation of the feed-advance eccentric. Fig. 5 is a fragmentary view of the work-arm with its cover-plate removed and showing the adjusting-member controlling device in top plan. Fig. 6 comprises a vertical-transverse section of the controlling device, and illustrates the controlling device operating button in side elevation.

The drawing illustrates the present improvement as embodied in a feed-off-arm sewing machine such as shown and described in the U. S. patent of W. Myers, No. 1,999,978, April 30, 1935. The sewing machine has the usual frame including a horizontally disposed hollow work-arm 10 supported by a carrier-arm 11 which is coplanar with the work-arm. The work-arm 10 comprises a trough-shaped casing closed at its top by a detachable cover-plate 12 which includes a separately detachable throat-plate 13. The cover-plate 12 is secured upon the work-arm in a manner to provide an oil-tight closure and comprises, in effect, a wall of the work-arm frame.

Journaled in the carrier-arm 11 to extend transversely of the work-arm 10 is a rotary actuating shaft 14; one end of said shaft being journaled in a ball-bearing 15 disposed in one

wall of the work-arm 10. Carried by the shaft 14 for rotation therewith are bevel-gears 16 and 17 for driving suitable loop-takers disposed within the work-arm 10 at the free end thereof for cooperation with needles, as 18, in the formation of stitches.

The work is advanced longitudinally of the work-arm 10 and off the free end thereof by a feed-dog 19 operating through the suitably slotted throat-plate 13 and opposed by a presser-foot 20. The feed-dog 19 is carried by one end of a feed-bar 21 extending longitudinally of and within the work-arm 10; said feed-bar being suitably fulcrumed for rocking and endwise movements upon a bracket 22 rising from the bottom wall of the work-arm.

The feed-bar 21, at its end opposite the feed-dog, is integrally provided with a laterally offset fork 23 straddling a feed-lift eccentric 24 carried by the actuating shaft 14 for rotation therewith. The eccentric 24 imparts rocking movements to the feed-bar 21 and therefore rising and falling movements to the feed-dog 19.

Secured, by screws 25, upon the feed-bar 21 for adjustment lengthwise thereof, is the shank 26 of a fork 27 slidably straddling a block 28 embracing a feed-advance eccentric 29; the fork 27 extending transversely of the feed-lift fork 23 whereby the eccentric 29 imparts endwise reciprocatory movements to the feed-bar 21. The feed-advance eccentric 29 is secured upon the actuating shaft 14, within the work-arm 10, for adjustment of the eccentricity of the eccentric; the construction of the eccentric 29 corresponding substantially with the eccentric disclosed in the U. S. patent to A. Grieb, No. 1,605,937, Nov. 9, 1926.

In general, the actuating eccentric 29 embraces an adjusting eccentric 30 associated therewith and disposed upon the shaft 14 for angular adjustment about said shaft. The eccentric 29 has a flange 31 provided with a radial slot 32 in which a pivot-block 33 is slidingly disposed. The pivot-block 33 is carried by a shouldered anchor-pin 34 projecting from a side face of a supporting disk 35. The disk 35 is seated upon the hub-extension 36 of the loop-taker actuating bevel-gear 16 and is suitably secured to said bevel-gear for rotation therewith. Consequently, the anchor-pin 34 constitutes a driving connection for rotating the eccentric 29 from the shaft 14.

The anchor-pin 34 extends freely through an arcuate slot 37 provided in a flange 38 of the adjusting-eccentric 30; the flange 38 being disposed between the flange 31 of the eccentric 29

and the supporting disk 35. The adjusting-member, comprising the eccentric 30 and its flange 38, is secured to the supporting disk 35 for rotation therewith during the normal operation of the machine, but in a manner permitting relative turning movements of said adjusting member and supporting disk for purposes of adjustment of the eccentricity of the eccentric 29. To that end, the side face of the adjusting-member flange 38, adjacent the eccentric-flange 31, is provided with an annular groove 39 affording a clearance recess for a friction-plate 40 and for the heads of screws 41 passing freely through the arcuate slot 37 in the flange 38; said screws 41 being threaded into the supporting disk 35. Friction-washers 42 are preferably interposed between the friction-plate 40 and the heads of the screws 41.

The flange 38 of the adjusting member is peripherally provided with a stop-notch 43 adapted to receive a detent which is manually operable to hold said adjusting member against rotation with the shaft 14. It is a specific object of the present invention to provide an oil-tight detent device readily operable from the exterior of the work-arm 10 for restraining the adjusting-member 30, 38 against rotation while effecting adjustment of the actuating eccentric 29 by turning the shaft 14.

In accordance with the present improvement, a bearing-block 44 is secured by screws 45 to the under or inner face of the cover-plate 12 which comprises a wall of the hollow work-arm 10. In its face proximate to the cover-plate 12, the bearing-block 44 is provided with a clearance-recess or cavity 46 which is closed inwardly of the work-arm by the oil-guarding bottom wall of the bearing-block. Opening into the bearing-block cavity 46 is an aperture 47 provided in the cover-plate 12 vertically above said cavity.

The bearing-block 44 is horizontally apertured to provide a bearing for a spindle 48 confined to rocking movement in the bearing-block. One end of the spindle 48 carries a lateral arm 49 which is shouldered at its free end to provide a detent 50 adapted to engage the adjusting device 30, 38, in the stop-notch 43 thereof. The detent-arm 49 is confined to move in a clearance-notch 51 provided in a narrow extension 44' of the bearing-block and cut into said extension from the under side thereof. The clearance-notch 51 therefore confines the spindle 48 against endwise movement, while the detent-arm 49 and the block-extension 44' function as oil-guards for the spindle bearing aperture of the block 44.

The other end of the spindle 48 extends into the bearing-block cavity 46 and is provided in said cavity with a crank-arm 52 having a split end thereof clamped upon the spindle 48 by a screw 53. The other end of the crank-arm 52 is provided with a recess 54 entered by a spring 55 interposed between the crank-arm and the bottom wall of the bearing-block cavity 46. The spring 55 biases the spindle 48 upwardly into a position of the detent-arm 49 retracted from the adjusting device notch 43.

The upper face of the spindle crank-arm 52 is provided with a contact rib 56 engaged by the under face of a manually operable push-button 57 movably disposed in the aperture 47 of the cover-plate 12 so as to be readily accessible exteriorly of the work-arm 10. The aperture 47 is undercut at the inner face of the cover-plate 12 to receive a peripheral rib 58 of the push-button 57, thereby limiting outward movement of the

push-button and determining the retracted position of the detent 50 under the action of the spring 55. The leverage afforded by the spindle crank-arm 52 provides for manual operation of the detent 50 with a minimum of effort.

At the end of the work-arm 10 connected to the carrier-arm 11, the frame of the machine is shaped to provide a well 59 adapted to contain a supply of lubricant into which dips the feed-actuating mechanism. In the operation of the machine, the work-arm is filled with an oil-mist due to the oil-splashing action of the feed actuating mechanism, and it is essential that oil will not escape through the cover-plate aperture 47 and be deposited upon the outer face of the work-arm 10. By housing the endwise movable push-button 57 and the crank-arm 52 in the cavity 46 of the cover-plate bearing-block, and by transmitting the movement of the push-button 57 to the detent 50 by means of a rocking spindle journaled in the bearing-block, the likelihood of discharging oil through the cover-plate aperture 47 upon operation of the push-button is eliminated.

Having thus set forth the nature of the invention, what I claim herein is:

1. A sewing machine having a hollow frame including a wall provided with a cavity closed inwardly of said frame, a rotary actuating eccentric adjustably disposed within said hollow frame externally of said cavity, an adjusting device associated with said eccentric within said frame, a detent disposed within said frame externally of said cavity for engagement with said adjusting device, and connections for actuating said detent including a manually operable member accessible from the exterior of said frame and extending into said cavity, said detent being spaced from said member a substantial distance laterally of the path of movement of said member.

2. A sewing machine having a hollow frame including a wall provided with a cavity closed inwardly of said frame, a rotary actuating eccentric adjustably disposed within said hollow frame, an adjusting device associated with said eccentric within said frame, a spindle journaled for rocking movement in said wall of the frame and having one end thereof extending into said cavity, a detent carried by the other end of said spindle for engagement with said adjusting device, and means for rocking said spindle including a manually operable member accessible from the exterior of said frame and extending into said cavity.

3. A sewing machine having a hollow frame including a wall provided with an aperture, a rotary actuating eccentric adjustably disposed within said hollow frame, an adjusting device associated with said eccentric within said frame, a spindle journaled in said wall for rocking movement and extending transversely of said aperture, a detent carried by one end of said spindle within said frame for engagement with said adjusting device, and means for rocking said spindle including a manually operable button endwise movably disposed in said aperture of the frame.

4. A sewing machine having a hollow frame, a rotary actuating eccentric disposed within said hollow frame and adjustable as to eccentricity, an adjusting device associated with said eccentric within said frame, a bearing-block extending from a wall of the frame and recessed to provide a cavity closed inwardly of said frame, a spring-biased spindle journaled for rocking move-

ment in said bearing-block, a detent carried by one end of said spindle for engagement with said adjusting device, and means for rocking said spindle from the exterior of said frame including a crank-arm carried by the other end of the spindle within said cavity.

5. A sewing machine having a hollow oil-tight frame including a detachable cover-plate provided with an aperture, a rotary actuating eccentric disposed within said hollow frame, an adjusting device associated with said eccentric, a

bearing-block carried by the inner face of said cover-plate and having a wall providing an oil-guard closure for said aperture inwardly of said frame, a detent disposed within said frame and pivotally mounted upon said bearing block for engagement with said adjusting device, detent-actuating connections carried by said bearing-block, and means operable through said aperture for actuating said connections.
